UNITED STATES PATENT OFFICE

WYNDHAM R. MADDEN, OF BAMBERTON, VANCOUVER ISLAND, BRITISH COLUMBIA,
CANADA

STIRRUP FOR CONCRETE REINFORCING UNIT

Application filed October 11, 1928. Serial No. 311,879.

The present invention relates to improvements in metallic reenforcing units that are embedded within a column, beam or the like formed of plastic material, and has for its 5 principal object to provide a stirrup for connecting the spaced rods of the reenforcing unit or structure together.

A further object is to provide a stirrup that is capable of longitudinal adjustment depending upon the distances between the spaced rods of the reenforcing structure that are to be connected together, means being provided for securing the adjustable stirrup in its predetermined adjusted position.

15 Still a further object is to provide a stirrup of the above mentioned character that is simple in construction, inexpensive, strong and durable and further well adapted to the purpose for which it is designed.

20 Other objects and advantages of the invention will become apparent from the following description when taken in connection with the accompanying drawings.

In the accompanying drawing wherein like 25 reference characters indicate corresponding parts throughout the same:

Figure 1 is a cross sectional view through a metallic reenforcing structure showing my improved stirrup connecting the rods of the 30 reenforcing structure together.

Figure 2 is an edge elevation of one of the stirrups per se.

Figure 3 is a view at right angles to Figure 2, the locking sleeves being shown in section.

Figure 4 is a transverse section taken approximately on the line 4-4 of Figure 3, and

Figure 5 is a detail perspective view of one 40 of the slidable locking sleeves forming a salient part of the present invention.

In the drawing wherein for the purpose of illustration is shown the preferred embodiment of my invention, the numerals 1, 2, 3, and 4 designate the usual spaced rods that 45 constitute the reenforcing structure for a concrete pole, column, beam or the like, and these reenforcing rods are embedded within the plastic structure in the manner well known in the art. It is one of the principal 50 aims of the present invention to provide a

means for connecting the adjacent rods of the reenforcing unit or structure together so that said reenforcing elements will be properly maintained in position during the construction of the plastic beam, post, column 55 or the like, and to this end I have provided an improved stirrup shown generally at 5.

This stirrup comprises a pair of complementary units denoted by the reference characters 6 and 7. Each unit is formed from an 60 elongated strand of wire that is bent back upon itself to form an eye 8 and elongated arms 9 and 10. As is clearly shown in Figure 2, the eye portion 8 of each unit is disposed at substantially right angles with respect to the 65 arms 9 and 10. Each arm is crimped throughout the entire length thereof, and as is clearly shown in Figure 3, and the crest or crown portions of one arm interfit with the trough portions of the opposite arm, and this feature is 70 also clearly illustrated in Figure 3. The arms of each unit are furthermore disposed in the same plane with each other and the free ends of the arms of one unit have sliding interfitting relation with the free ends of the arms of 75 the opposed unit, and it is of course to be understood that the crimps formed in each arm are identical so that said units may be properly disposed in interfitting relation.

The eye portions 8 are disposed around the 80 respective pair of spaced rods; and for the purpose of securing the complementary units 6 and 7 of each stirrup together, I provide a pair of locking sleeves shown at 11. Each locking sleeve is formed from a relatively 85 wide strip of metal bent back upon itself to provide a flat loop, and the sleeves are of such width as to permit the same to slide along the interfitting and interlocked crimped arms of the opposed unit. Each locking sleeve is 90 preferably of such length as to cover a little over the distance between one pair of adjacent crests as indicated in Figure 3. When the locking sleeves are positioned on the complementary units of each stirrup in the manner shown in Figure 3, said units are locked together so that the same cannot be moved toward or away from each other, and consequently the reenforcing rods engaged by the 95 eyes of these particular units will be main- 100

tained in their proper spaced relation with respect to each other.

When it becomes necessary to move the rods of the reenforcing structure either toward or away from one another, the slideable sleeves 11 are moved toward the respective eyes so that said sleeves, will be solely upon the arms of the respective unit, and due to the resiliency of the wire from which the units are formed, the crimped arms will be sprung outwardly so as to enable said units to be either moved toward or away from each other, and after the units have been properly adjusted, the sleeves 11 are again slid inwardly for disposition over the free end portions of the opposite arms, and the intermediate portions of the adjacent arms, thus causing the crimped arms to be disposed in interfitting and interlocked engagement, and all the arms will be disposed in the same horizontal plane, and confined within the locking sleeve, as shown in Figure 4.

As disclosed very clearly in Figure 1, the stirrups will maintain the reenforcing rods in proper spaced relation, and in addition the diagonally opposed reenforcing rods may be connected together by similar stirrups.

The provision of a stirrup construction of the above mentioned character will enable the same to be readily and easily attached to the reenforcing metallic structure that is to be embedded within a concrete or plastic beam, post or the like.

Further, the parts comprising each stirrup can be readily and easily adjusted, and when the proper adjustments have been made, the stirrup will be retained in its position for securing the rods in the reenforcing structure together in such a manner as to prevent casual displacement of the stirrup. The simplicity of my stirrup enables the same to be constructed at a very low cost, and will at all times be positive and efficient in carrying out the purposes for which it is designed.

While I have shown the preferred embodiment of my invention, it is to be understood that minor changes, in the size, shape and arrangement of parts may be resorted to without departing from the spirit and scope of the appended claims.

Having thus described the invention, what I claim as new and desire to secure by Letters Patent is:—

1. A stirrup for connecting together a pair of spaced rods of a concrete reenforcing structure comprising a pair of opposed complementary units, each unit being formed from a single strand of spring wire bent back upon itself to form an intermediate eye and a pair of elongated arms, the eye portion of each unit being adapted for disposition around the respective rod of the reenforcing structure, the arms of each unit being crimped, the crests of one arm having interfitting re-

lation with the troughs of the other arm of each unit, the crimped arms of one unit having interfitting relation with the crimped arms of the opposed unit, and means cooperating with the interfitting crimped arms of the opposed units to secure said units in any longitudinally adjusted position. 70

2. A stirrup for connecting together a pair of spaced rods of a concrete reenforcing structure comprising a pair of opposed complementary units, each unit being formed from a single strand of spring wire bent back upon itself to form an intermediate eye and a pair of elongated arms, the eye portion of each unit being adapted for disposition around the respective rod of the reenforcing structure, the arms of each unit being crimped, the crests of one arm having interfitting relation with the troughs of the other arm of each unit, the crimped arms of one unit having interfitting relation with the crimped arms of the opposed unit, means cooperating with the interfitting crimped arms of the opposed units to secure said units in any longitudinally adjusted position, 75 80 85

3. A stirrup for concrete reenforcing units comprising a pair of complementary units, each of which is provided with means for connection to a reenforcing element, and a shank presenting spaced longitudinally crimped arms, the arms of one unit being adapted to be engaged in the other unit, 90 95 100 105 said arms being of resilient material normally flexed so as to spring away from one another, and a confining member slideable on each shank and adapted when engaged over the crimped portion of the unit to retain the interdigitated arms thereof in fixed relation.

In testimony whereof I affix my signature.
